Fig. 2.

Fig. 3.

Fig. 4.

FIGURE 1 is a perspective view of a combined room humidifier and medicinal vaporizer or the like embodying my design;

FIGURE 2 is a view of one side thereof on an enlarged scale, the opposite side being identical;

FIGURE 3 is a view of an adjacent side thereof on an enlarged scale, its opposite side being identical; and

FIGURE 4 is a top plan view thereof on an enlarged scale.

FIGURE 5 is an enlarged sectional view taken on line 5—5 of FIGURE 1.

The dominant features of my design reside in those portions thereof shown in full lines.

The broken line representation of a mask and a hose has been omitted from FIGURES 2, 3 and 4, for convenience of illustration.

I claim:

The ornamental design for a combined room humidifier and medicinal vaporizer or the like, as shown and described.
